MUFFLING DEVICE

Elliott E. Grover, Springfield, Mass., assignor
to Westinghouse Electric & Manufacturing
Company, East Pittsburgh, Pa., a corpora-
tion of Pennsylvania

Application November 27, 1934, Serial No. 754,967

2 Claims. (Cl. 181—35)

My invention relates to muffling devices and to a method of manufacturing such devices, for use particularly with gas compressors.

It is an object of my invention to provide a 5 unitary muffler construction which is easily assembled and inexpensively formed.

It is another object of my invention to provide an effective muffling device for the compressor of mechanical refrigerating apparatus.

10 These and other objects are effected by my invention, as will be apparent from the following description and claims taken in connection with the accompanying drawings forming a part of this application, in which:

15 Fig. 1 is a view of a mechanical refrigerator of the compression type with parts thereof broken away to show the compression apparatus;

Fig. 2 is a plan view of a muffling device constructed in accordance with my invention;

20 Fig. 3 is a sectional view of the muffling device taken on line III—III of Fig. 2;

Fig. 4 is a side view of the muffler construction shown in Fig. 2;

25 Fig. 5 is a side view of a baffle member which forms a part of the muffling device; and,

Fig. 6 is a front view of the baffle member.

Referring specifically to the drawings for a detailed description of my invention, a complete mechanical refrigerator 10 is shown in Fig. 1.

30 The mechanical refrigerator 10 comprises a hermetically sealed casing 11 which encloses a motor, (not shown), and a compressor 12. A condenser 13 is provided for condensing refrigerant vapor compressed by the compressor 12; the condenser being cooled by a fan 14. An evaporator 15 is supplied with liquid refrigerant through the intermediary of a float controlled valve 16, which liquid refrigerant is vaporized in the evaporator 15 and absorbs heat therefrom. A 35 unitary muffling device, generally indicated at 17, is associated with compressor in a manner hereinafter fully described.

Referring specifically to Figs. 2 to 6, the muffler construction generally referred to by numeral 17 45 comprises two flat metal plates 18 each having sets of three complementary corrugations 19 stamped therein. The plates 18 are welded or otherwise fastened together at their meeting edges and between corrugations 19, to form a 50 unitary muffling device embodying three muffling chambers 21, 22 and 23 therein. Before welding the plates 19 together, a pair of discs 24 fastened together by a spacing member 25 (see Figs. 5 and 6) are fastened interiorly of each muffling chamber by welding the spacing members 25 to

the interior of one of the corrugations 19. The discs 24 are provided with apertures 26 to restrict the passage of gas through the muffling chambers 21, 22, and 23, the apertures 26 being axially offset to direct gases passing through 5 the muffling chambers 21, 22, and 23 in a tortuous path, whereby the muffling devices effectively deaden the sound of gas passing therethrough. As shown in Figs. 5 and 6, the discs 24 and spacing member 25 are preferably formed 10 from a single stamping bent to the desired shape.

A connecting passage 27 opens between muffling chambers 21 and 22. The connecting passage 27 is formed by depressing complementary portions 28 in the plates 18 adjacent one end of the chambers 21 and 22. An inlet passage 29 is provided at the opposite end of the muffling chamber 22 from the connecting passage 27. An outlet passage 31 is provided at the opposite end of the 20 muffling chamber 21 from the connecting passage. A second inlet passage 32 is provided at one end 20 of the muffling chamber 23 and a second outlet passage 33 is provided at the opposite end of the chamber 23.

25 Apertures 34 are provided in the plates 18 to receive fastening devices for attaching the unitary muffling device to a portion of the compression means 12.

The operation of the mechanical refrigerating 30 apparatus embodying my improved muffling device is as follows: Vaporized refrigerant which has absorbed heat from the evaporator 15 is withdrawn from the evaporator by the suction of compressor 12 and is conveyed through a conduit 35 to the sealed casing 11. From sealed casing 11, vaporized refrigerant is conveyed to inlet 29 of muffling chamber 22 through a conduit 30. The vaporized refrigerant is then drawn through muffling chamber 22, passage 27 and 35 muffling chamber 21 to outlet 31 of chamber 21. The gas in passing through chambers 22 and 21, passes through the baffle members 24, and the sound of the gas is thereby deadened. The gas is 40 conveyed through a conduit 36 from outlet 31 45 of muffling chamber 21 to the compressor 12.

The gaseous refrigerant thus conveyed to compressor 12 is compressed thereby, and is conveyed through a conduit 37 to the inlet 32 of muffling chamber 23. The compressed gas is then forced 50 through the muffling chamber 23 to the outlet 33 thereof, the sound of the gas being deadened by the baffle members 24 in muffling chamber 23. The compressed gas is then forced to the condenser 13 through a conduit 38. The gaseous 55

refrigerant is cooled by air forced over the condenser 13 by the fan 14, and is condensed.

Condensed refrigerant is conveyed to the evaporator 15 by a conduit 39, having the float controlled valve 16 interposed therein for regulating the flow of refrigerant liquid to the evaporator, and the cycle is then repeated.

It is desirable to provide two chambers for the passage of gas from the cooling element 15 to the compressor 12 because there is little restriction in this part of the system to assist in deadening the sound of the gas passing therethrough. The apertures 26 in the discs 24 disposed in muffling chamber 23 are smaller than those in the discs disposed in muffling chambers 21 and 22. The gas passing through the muffling chamber 23 being at high pressure occupies less volume per unit of weight, and the high pressure gas must, therefore, be baffled to a greater extent by making the apertures 26 small in order to effectively deaden the sound of the moving gas.

From the foregoing, it will be apparent that I have provided an effective unitary muffling device which is inexpensively formed. The muffling device is particularly applicable to compression refrigeration apparatus but is not to be limited to such use, as it may be effectively employed with any type of gas compressor.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. A multiple muffler construction for a gas compressor comprising two flat metal wall members, and a plurality of complementary depressions formed in each wall member, said wall members being juxtaposed and welded around the edges and between the depressions to form a plurality of muffling chambers, one of said muffling chambers being connected to receive the discharge gas from said compressor, and another of said muffling chambers being connected to receive the intake gas for said compressor, whereby the entire mass of the metal of said muffler construction deadens the pulsations of the discharge and intake gas from and to said compressor. 5

2. A multiple muffler construction for a gas compressor comprising two flat metal wall members, a plurality of complementary depressions formed in each wall member, said wall members being juxtaposed and welded around the edges and between the depressions to form a plurality of muffling chambers, one of said muffling chambers being connected to receive the discharge gas from said compressor, and another of said muffling chambers being connected to receive the intake gas for said compressor, and a baffling member for the muffling chambers comprising a single piece of metal bent to substantially U-shape, the bottom of the U being fastened to an internal wall of a muffler chamber, and the legs of the U extending transversely of and conforming with the shape of the muffling chamber and being provided with apertures therein for the passage of gas, the bottom of the U-shaped baffling member serving as a spacer and as an attachment for legs thereof. 10 20 25 30 35
